UNITED STATES PATENT OFFICE.

ISIDORE CLAIR, OF BROOKLYN, NEW YORK.

VACUUM SCALP CLEANING AND VIBRATING MACHINE.

Application filed May 19, 1922, Serial No. 562,280. Renewed February 4, 1927.

This invention relates to scalp cleansing apparatus and has for its object the provision of a device which may be used to cleanse and massage the scalp.

- 5 An important object of the invention is the provision of a device which may be applied to the head of a person and which will brush the hair gently and allow the dandruff etc., to be drawn therefrom.
- 10 Another object of the invention is to provide a device which in one instance will be self-contained and which in another will be operated from a remote source of power.

A further object is to provide a device 15 wherein a brush may be used which will be rotated, and so held that it may be readily replaced by a vibrator brush so that vibratory treatment may be imparted to the scalp.

Referring to the drawings forming part 20 of this application;

Fig. 1 is an elevational view, partly in section, of a form of my invention embodying the motor, and comprising a compact device,

25 Figure 2 is a front elevational view of the device as illustrated in Figure 1, a portion thereof being shown in section.

Figure 3 is a view similar to Figure 2 with parts removed, the section being taken 30 to expose the revolving brush element,

Figure 4 is a section showing the brush operating mechanism.

Figure 5 is a side elevation of the mechanism as illustrated in Fig. 4, the brush being shown in outline.

Figure 6 is a perspective view of the vibrator element.

Fig. 7 is a perspective view of the vibrator housing.

Fig. 8 is a view in elevation of a brush used in the device which is formed to fit the contour of the head.

Fig. 9 is a perspective view of the vibrator brush or massage implement.

45 Fig. 10 is a side view of a portion of the device illustrating the brush and vibrator driving mechanism, the casing for the same being outlined.

Figure 11 is a broken front view of the head device showing the arrangement of the upturned teeth.

Fig. 12 is a view in perspective of a form 55 of my device wherein the power delivering apparatus and suction fan are mounted upon a stand, so that a smaller and more compact device may be applied to the scalp.

Figure 13 is an elevation, partly in section of the head engaging member as illustrated in Fig. 12.

Figure 14 is a section taken on the line 60 14—14 of Fig. 13.

Figure 15 is a perspective view of a portion of the head engaging member showing the operating mechanism housing.

Figure 16 is a perspective view of a brush cleaning comb.

Figure 17 is a side view of the upper portion of Figure 3.

Referring to the drawings in detail, a motor denoted by 10 of the usual hand vibrator type commonly used, includes a motor shaft 11 on the end of which adjacent the motor is mounted a suction fan 12.

Surrounding the motor and forming a 70 housing for the whole device is a casing 13 which extends downwardly from the motor to form a head engaging part, the bottom 14 of which is formed to comprise longitudinal flutes 15 through which the air may be drawn and through which the revolving 80 brush 17 projects.

The front end of the casing is formed at its lower edge with slightly upturned teeth 18 which act to separate the hairs before the same are acted upon by the brush.

The end of the shaft 11 is journaled in the casing and carries a gear 19 preferably of the helical type which is provided with a clutch face and which is loosely mounted on the drive shaft, the opposing clutch member 20 being keyed to the shaft, so that it will carry with it in revolving, the gear 19. The gear 19 and clutch formed thereon are shifted to free position through the medium of a pivoted lever which projects through 90 the casing 13, for the purpose of allowing the suction fan to operate independently of the brush.

A wall 21 is fastened within the casing 13 and forms a dust tight compartment within which the drive gearing is disposed. A 100 stub shaft 22 carrying a worm gear 23 is mounted between the casing and wall 21 and said worm gear meshes with a worm 24 mounted on a stub shaft 25 journaled in the compartment walls 26. The stub shaft 25 has joined thereto the flexible shaft 27 which extends through a hole in the casing and passes through a housing 27' exterior thereto to the bevel gear 28 which meshes with and drives a bevel pinion 29.

The pinion 29 is provided with a hub 30

which is journaled in the casing wall, and has a ratchet wheel 31 formed thereon which lies within the casing and also within a suitable housing 32, the latter of which prevents the hair of the head from becoming tangled in said ratchet.

The ratchet 31 at its center has a square bore 33 within which fits the square end 34 of the brush core 35, the other end of the core being provided with a cone pivot 36 which fits within a suitable yielding center member 37, said member being yieldable for the purpose of inserting the brush 17.

The housing 32 is shaped to conform to the contour of the ratchet wheel 31 with the exception of the top, which is elongated to form a guideway 38 within which a hollowed square journal member or vibrator 39 may have vertical reciprocatory movement. The vibrator 39 is provided with a downwardly projecting pin which rests upon the periphery of the ratchet and is maintained thereagainst by a spring 40 between the top of said vibrator and the under side of the casing.

The housing 32 is provided with a rectangular opening with which the square hole in the vibrator will register at all times, and the housing is suitably fastened as by screws to the casing 13.

When it is desired to use the massage brush 41 having the usual rubber teeth 42, the hair brush 17 is removed, and the brush 41 inserted, a pivotal end 43 being provided thereon as in the brush 17 for engagement with the yielding center member 37. A bracket 44 having a squared portion 45 formed thereon is attached to the end of the brush permanently, and the squared portion 40 is inserted into the vibrator 39. This allows the brush teeth to project about the same relative distance out of the casing 13 as do the bristles of the rotating hair brush 17.

When, therefore, the flexible shaft is driven through the operation of the clutch member as described, the hair brush 17 will rotate and the vibrator 39 will have reciprocating movement, the latter not causing any movement of the brush, but when the hair brush 17 is removed and the massage brush 41 inserted into the vibrator there will be only a vibratory movement of said brush, as can be seen by inspection of Figures 4, 5 and 18.

A suitable oiling cap 46 may project through the casing 13 into the gear compartment.

In the device illustrated in Figures 12 and 13, the motor, fan and operating mechanism are mounted upon a stand 47, which also supports a receiving bag. The dust drawn through the head engaging member 49 and the hose 48 is deposited in said receiving bag.

The gearing is similar to that before described and is enclosed by the case 50 through

which projects the clutch operating lever 51.

A suitable rheostat 52 may be used in conjunction with the motor to regulate the speed thereof and thereby the fan and brush speeds.

In the form shown in Figure 1 the exhaust 70 from the suction fan 12 passes through a flue 53 which may be attached to the outside on the motor casing and to which may be attached a pipe or hose similar to 48, illustrated in Figure 12.

In Figure 16, a brush cleaning comb 54 is shown having a bracket 44 generally similar to the bracket 44 of the brush 41 attached thereto, the comb being placed in the same position as the brush 41 so that when the suction is maintained by the fan 12, the drawing of a hair brush across the teeth of the comb will loosen the dirt therein and the suction will draw the same therefrom. The comb 54 is provided with the pivot 43 85 also. When said comb is in use, the vibrator of course is stationary.

In order to shut off the suction when using the device as a vibrator, a damper 55 of any approved type may be mounted in the air 90 passage, for sliding movement, to cut off the intake of air.

What I claim is:

1. In a device suitable for the treatment of the human head, in combination a motor, a 95 revolvable motor shaft carried by the motor, a suction fan fixedly attached to the motor shaft, a clutch fixedly attached to the motor shaft, a free clutch carried by the motor shaft capable of meshment with the fixed 100 clutch, means for making and breaking the clutch engagement, means whereby the revolution of the motor shaft when in clutch engagement will revolve a brush bearing having an angular recess within its inner 105 end, a ratchet wheel revoluble with the brush bearing, a vertically slideable member above the ratchet wheel having an angular opening therein and a pin carried by the slideable member capable of movable engagement over the teeth of the ratchet wheel.

2. In a device suitable for the treatment of the human head, in combination a housing, a motor, a revolvable motor shaft carried by the motor, a clutch fixedly attached to the motor shaft, a free clutch carried by the motor shaft capable of meshment with the fixed clutch, means for making and breaking the clutch engagement, means whereby the revolution of the motor shaft when in clutch engagement will revolve a brush bearing having an angular recess within its inner end, a ratchet wheel revoluble with the brush bearing, a vertically slideable member above the ratchet wheel having an angular opening 125 therein, a pin carried by the slideable member capable of movable engagement over the teeth of the ratchet wheel, a second brush bearing having an annular opening therein, and a partition wall within the housing sepa- 130

rating the fan from the other elements of the device allowing the upward passage of air through the fan chamber.

3. In a device suitable for the treatment of the human head, in combination a housing, a motor, a revoluble motor shaft carried by the motor, a clutch fixedly attached to the motor shaft, a free clutch carried by the motor shaft capable of meshment with the fixed clutch, means for making and breaking the clutch engagement, means whereby the revolution of the motor shaft when in clutch engagement will revolve a brush bearing having an angular recess within its inner end, a ratchet wheel revoluble with the brush bearing a vertically slidale member above the ratchet wheel having an angular opening therein, a pin carried by the slidale member capable of movable engagement over the teeth of the ratchet wheel, a second brush bearing having an annular opening therein, a partition wall within the housing separating the fan from the other elements of the device allowing the upward passage of air through the fan chamber, and a bottom to the housing having an opening therein allowing the outward extension of a brush carried by the brush bearings.

4. In a device suitable for the treatment of the human head, in combination a housing, a motor, a revoluble motor shaft carried by the motor, a clutch fixedly attached to the motor shaft, a free clutch carried by the motor shaft capable of meshment with the fixed clutch, means for making and breaking the clutch engagement, means whereby the revolution of the motor shaft when in clutch engagement will revolve a brush bearing having an angular recess within its inner end, a ratchet wheel revoluble with the brush bearing, a vertically slidale member above the ratchet wheel having an angular opening therein, a pin carried by the slidale member capable of movable engagement over the teeth of the

ratchet wheel, a second brush bearing having an annular opening therein, a partition wall within the housing separating the fan from the other elements of the device allowing the upward passage of air through the fan chamber, a bottom to the housing having an opening therein allowing the outward extension of a brush carried by the brush bearings, and openings therein for the admission of air caused by the suction action of the fan.

5. In a device suitable for the treatment of the human head, in combination a housing, a motor, a revoluble motor shaft carried by the motor, a clutch fixedly attached to the motor shaft, a free clutch carried by the motor shaft capable of meshment with the fixed clutch, means for making and breaking the clutch engagement, means whereby the revolution of the motor shaft when in clutch engagement will revolve a brush bearing having an angular recess within its inner end, a ratchet wheel revoluble with the brush bearing, a vertically slidale member above the ratchet wheel having an angular opening therein, a pin carried by the slidale member capable of movable engagement over the teeth of the ratchet wheel, a second brush bearing having an annular opening therein, a partition wall within the housing separating the fan from the other elements of the device allowing the upward passage of air through the fan chamber, a bottom to the housing having an opening therein allowing the outward extension of a brush carried by the brush bearings, openings therein for the admission of air caused by the suction action of the fan, and outwardly extended spaced teeth carried by the lower forward extremity of the housing.

Signed at New York, in the county of New York and State of New York, this 9th day of January, A. D. 1922.
